UNITED STATES PATENT OFFICE

JASPER B. WILLIS, OF LOS ANGELES, CALIFORNIA

TIMING DEVICE

Substitute for application Serial No. 683,788, filed December 31, 1923. This application filed April 21, 1930. Serial No. 446,126.

This application is a substitute for application Serial No. 683,788, filed December 31, 1923.

This invention relates to indicators, particularly to attachments for automobile engines, and has for its object the provision of a device designed to be screwed into the spark plug opening of an automobile engine or in fact any other engine of the internal combustion engine type, the device being so constructed as to apprise the operator of any error in the timing of the explosion within the engine cylinder.

An important and more specific object is the provision of a device of this character which embodies a movable element which is operated by the compression within the engine cylinder and which cooperates with a relatively stationary contact point whereby the exact position of the engine piston at the time of the occurrence of the spark may be ascertained so that any error may be easily remedied.

A still further object is the provision of a device of this character which will operate to indicate not only an error in the timing but also the degree of error and whether the explosion occurs too late or too early.

An additional object is the provision of an apparatus of this character which will be simple and inexpensive in manufacture, and installation, highly efficient in use, durable in service and a general improvement in the art.

With the above and other objects and advantages in view, the invention consists in the details of construction to be hereinafter more fully described and claimed and illustrated in the accompanying drawings, in which:

Figure 1 is an elevation of the device showing it in applied position,

Figure 2 is a longitudinal section,

Figure 3 is a cross sectional view taken on the line 3-3 of Figure 2.

Referring more particularly to the drawings the letter A designates a fragment of an engine having the usual spark plug receiving hole B therein. In carrying out my invention I provide a metallic body 10

formed with a bore 11 and having a threaded end 12 for engagement within the opening B. This body is formed with faces which permit engagement of a wrench therewith for facilitating turning movement. Rising 55 from and preferably integral with the body is an upstanding tubular guide 13 having its bore or interior coincident with the bore 11. The top of this guide is closed except for a central hole 14.

Surrounding this guide is an elongated tubular casing 15 of nonconducting material such as fiber, bakelite or the like, which casing is entirely open at its top and formed in one side with an elongated slot 16. Engaged upon the casing is a metallic cage designated broadly by the numeral 17 and including upper, intermediate and lower bands 18, 19 and 20 respectively, the former two of which are connected by spaced strips 21 and the latter two of which are connected by a single strip 22. The strips 21 are located at opposite sides of the slot 16 and for a purpose to be described. The lower band 20 carries binding screws 23 equipped with nuts 24 for connection of the ignition wire therewith. Only one screw is necessary but two are shown as it may be more convenient to connect with one than the other.

Slidable through the bore 11 and guide 13 is a plunger 25 carried by a stem 26 which is slidable through the hole 14 and which has its upper portion provided with a tapered reduction 27 defining a shoulder 28. Within the guide is a coil spring 29 engaging 80 against the top thereof and against the plunger 25 for normally opposing upward movement of the plunger.

Slidably mounted within the casing 15 above the guide 13 is a block 30 formed with a bore 31 slidably receiving the stem 26 and formed in one side with a slot 32 within which is pivoted at 33 an indicator arm 34. This arm is urged into engagement with the stem by a leaf spring 35 and it is provided with an outwardly extending finger 36 which passes through the slot 16 and which is equipped with a terminal head 37 constituting a contact, which head is spaced away from the strips 21 of the cage. An adjusted 100

position of the block 30 within the casing is maintained by the frictional engagement at the casing wall of a leaf spring 38 carried by the block and having projecting ends 39. The 5 stem 26 passes through and beyond the block 30 and is equipped above and below the same with stop collars 40 which serve as abutments for coil springs 41 which bear also against the faces of the block and which cushion the 10 shock of the movement of the parts when the device is in operation.

Slidable within the upper end of the casing above the block 30 is a plunger 42 carried by a stem 43 equipped with a knob 44. The 15 plunger 42 carries a leaf spring 45 which frictionally engages the inner wall of the casing for maintaining an adjusted position.

Assuming that the device has been constructed and assembled as above described, 20 the operation is as follows:—The spark plug is removed from the cylinder to be tested and the body 10 is screwed into the hole. By means of the plunger 42, the operator presses the block 30 and stem 26, together with the 25 plunger 25, downwardly. When the device is thus set, and the compression stroke of the engine occurs, it will be apparent that the pressure within the explosion chamber of the engine acting upon the piston 25 will 30 cause the latter to move upwardly against the resistance of the spring 29. The block 30 is naturally moved upwardly by the stem 26 and the operator may note the highest point reached by the indicator head 37. As the stem 35 26 moves upwardly, it is apparent that it will slide through the block 30 to a certain extent, and that the reduced portion 27 sliding against the arm 34 will cause the latter to swing laterally. As this occurs the head 40 37 approaches the right hand strip 21 so that a proper length of gap will be defined to permit a spark to jump across. The high tension current enters at either binding post 23, passes along the strips 22 and 21, across the 45 gap and through the rod 26 and body 10 to the ground. If the engine is properly timed, this spark will occur when the indicator is at its highest point. If the timing is too advanced the spark will occur before the indicator reaches the limit of its movement and the reverse will be true if timing is retarded or too late. In this way it will be seen that the operator may readily ascertain exactly 50 the condition of the timing of the engine and may make whatever adjustments are necessary to insure proper action. The device is bound to be a great time and labor saver and should therefore recommend itself to 55 those having occasion to employ its services.

While I have shown and described the preferred embodiment of my invention it is of course to be understood that I reserve the right to make such changes in the form, construction and arrangement of parts as will

not depart from the spirit of the invention or the scope of the subjoined claims.

What I claim is:

1. A device of the character described comprising a body adapted to be screwed into the spark plug opening of an engine cylinder, a support carried by said body, a spring pressed plunger operating within said body and having a stem, a frame secured upon said support and provided with means for attachment of an ignition wire, a movable sparking member cooperating with one side of said frame whereby to provide a spark gap, and means on the stem for moving the sparking member. 70

2. An indicator of the character described comprising a body having one end threaded for engagement within the spark plug opening of an engine cylinder, a support of insulating material carried by the upper end of said body, a downwardly spring pressed plunger operating within said body and having a stem movable along said support, a metallic frame carried by said support and provided with means for attachment of an ignition wire, and a sparking member cooperating with one side of said frame whereby to define a spark gap, said sparking member being rockably mounted, and means on the stem for moving the sparking member to one side upon the upstroke of the piston and to the other side upon the downstroke thereof. 85

3. An indicator of the character described comprising a body having one end threaded for engagement within the spark plug opening of an engine, a support of insulating material carried by the upper end of said body, a downwardly spring pressed plunger operating within said body and having a stem movable along said support, a metallic frame carried by said support and provided with means for attachment of an ignition wire, a block slidable within the support and through which the stem slides, a sparking member carried by said block terminating in a contact cooperating with one side of said frame whereby to define a spark gap, said sparking member being pivoted on said block, and wedge means on the stem for moving the sparking member to one side upon the upstroke of the piston and to the other side upon the downstroke thereof. 100

4. An indicator of the character described comprising a body having one end threaded for engagement within the spark plug opening of an engine cylinder, a hollow support of insulating material carried by said body, a downwardly spring pressed plunger operating within said cylinder and having a stem movable along said support, a metallic frame carried by said support and provided with means for attachment of an ignition wire, a block within the body having a bore for the passage of the stem, said stem having a tapered reduced portion within the block, 115

an arm pivoted in the block and spring pressed into engagement with the stem, and having a head adapted to cooperate with one side of said frame whereby to define a spark

5 gap.

5. An indicator of the character described comprising a body having one end threaded for engagement within the spark plug opening of an engine cylinder, a support of insulating material carried by said body, a downwardly spring pressed plunger operating within said body and having a stem movable along said support, a metallic frame carried by said support and provided with means for attachment of an ignition wire, a sparking member pivotally mounted within the support and engaged by said plunger and cooperating with one side of said frame whereby to define a spark gap, said sparking member

20 moving to one side upon the upstroke of the plunger and moving to the other side upon the downstroke thereof, and an indicator slideable along the support and moved upwardly by upward movement of said stem.

25 6. In a device of the character described, a combined supporting and enclosing member adapted to be engaged within the spark plug opening of an internal combustion engine, a spring pressed plunger mounted within said member and adapted to be moved by pressure within the engine cylinder, a frame on and insulated from said member, and a movable contact operatively engaged by said spring pressed member and co-acting

35 with the frame to define a spark gap.

7. In a device of the character described, a supporting member adapted to be engaged within the spark plug hole of internal combustion engine, a plunger slidably mounted within said member and adapted to be moved by pressure within the engine cylinders, metallic element insulated from said member, and means operated by movement of the plunger and co-acting with the metallic element to define a spark gap.

40 8. In a device of the character described, a member adapted for connection with an engine at a spark plug hole therein, a reciprocating element carried by said member and moved under the influence of pressure within the engine cylinder, and means actuated by said second named member for defining a spark gap.

In testimony whereof I affix my signature.
JASPER B. WILLIS.
